UNITED STATES PATENT OFFICE.

ASBURY C. VOWELL, OF LITTLE ROCK, ARKANSAS.

WINDOW SASH.

Application filed March 14, 1927. Serial No. 175,326.

This invention relates to improvements in window sash, and has for one object to so construct the sash that the sash cord may be placed or replaced without moving the sash 5 from the window frame.

Another object of the invention is to provide a window, including a sash, so constructed that the sash cord may be removed without removing the sash or its retaining strips.

10 With the above and such other objects in view as may hereinafter more fully appear, I have invented the device illustrated in the accompanying drawings, in which:

Figure 1 is an elevational view of a window 15 embracing my invention, partly in section.

Figure 2 is a section on line 2—2 of Figure 1.

Figure 3 is a section on line 3—3 thereof, both sash being in closed position.

20 Figure 4 is a similar view, showing certain parts removed.

Figure 5 is a longitudinal section on line 5—5 of Figure 2, illustrating a modification in the construction.

25 Figure 6 is a section on the line 6—6 of Figure 5.

Figure 7 is a sectional detail illustrating the device arranged for one single cord for each sash.

30 Figure 8 is a sectional detail illustrating a modification in the manner of arranging the weight cord.

Like reference characters indicate like parts throughout the specification and in the 35 several views in the drawings, in which:

1 indicates a window, including the frame 2 and upper and lower sash 3 and 4 respectively. The casing members 5 and 6 of the frame 2 are provided with hand holes or apertures 7 and 8, normally closed by ornamental closure blocks 9 and 10. The purpose of the hand holes 7 and 8 is in order that by removing the blocks 9 and 10 a person's hand may be inserted to withdraw window weights

40 45 11 and 12, in order to attach the end of the sash cords 13 and 14 thereto, the other portions of said cords having first been strung over the pulleys 15 and 16 and inserted through grooves 17, 18, 19 and 20 of the sash 3 and 4, said grooves extending the full length of said sash. The sash cords are then turned at right angles into the grooves 21

50 55 and 22, formed in the lower edges 23 and 24 of the sash 3 and 4, where the ends of said cords may be fixed, or if a single cord is used as illustrated, the cord may be fixed by sta-

ples or pulleys to prevent slipping thereof. It will be noted that in this arrangement, a single cord may be used for each sash, instead of two cords as is used in the present 60 method of attaching sash cords to the sash.

From the above description it will be seen that in order to replace a broken sash cord it will only be necessary to thread one end of the cord over pulley 15, inserting the hand through the aperture 7, removing the sash weight 11 through said aperture and fixing cord to said weight, after which the weight is replaced within the frame and the aperture closed. The other end of the cord is then threaded through the groove 17 in the sash 4, and then into the groove 21 in the sash 4 and up through the groove 18 in the side of said sash, and then over the pulleys 16. Then the block 10 is removed and the 65 end B of said cord is taken through the aperture 9 and the sash weight 12 also removed through said aperture and the end B attached thereto, after which the weight 12 is replaced and the closure member is replaced, and the 70 sash is properly hung. It will thus be seen that either or both of the sash may be hung within the frame 2, without removing the sash from the frame or removing any of the 75 retaining strips 25. Closure strips 26 and 27 are attached to the lower edges 23 and 24 of the sash 3 and 4, which strips may be either formed of wood of the same kind of which the sash are made, or set in metal strips. In either case, these strips are bevelled to 80 fit the slant of the sill.

The grooves in the lower rail of the sashes may be made in the outer faces instead of the lower face, as shown in Figures 5 and 6, and the metal covering plate attached to the 85 outer vertical faces of the sashes instead of upon the bottom, if preferred.

The grooves in the lower rails of the sashes may be arranged as shown in Figure 8, if found advantageous.

Having described my invention, that which I claim as new, and desire to protect by Letters Patent, is:

1. A device of the character described, including a window frame and sash hung therein, and single cord for supporting said sash, and weights attached to both ends of said cord.

2. A device of the character described, including a window frame and sash hung 105 therein, and single cord for supporting said sash, and weights attached to both ends of 110

said cord, said cord encircling three sides of said sash.

3. A device of the character described, including a window frame and sash hung therein, a single cord for supporting said sash, and weights attached to both ends of said cord, said cord encircling three sides of said sash, said sides being grooved throughout their length to receive said cord.

10 4. A device of the character described, including a window frame and sash hung therein, a single cord for supporting said sash, and weights attached to both ends of said cord, said cord encircling three sides of said sash, said sides being grooved throughout their length to receive said cord, a closure strip for one of said sides.

15 5. A device of the character described, including a window frame and sash hung

therein, a single cord for supporting said sash, and weights attached to both ends of said cord, said cord encircling three sides of said sash, said sides being grooved throughout their length to receive said cord, a closure strip for one of said sides, said frame having 20 hand holes.

5 6. A device of the character described, including a window frame and sash hung therein, a single cord for supporting said sash, and weights attached to both ends of 30 said cord, said cord encircling three sides of said sash, said sides being grooved throughout their length to receive said cord, a closure strip for one of said sides, said frame having hand holes, closures for said holes.

15 35 In testimony whereof I affix my signature.

ASBURY C. VOWELL.
